ALVA W. BLANCHARD, OF BROOKLYN, NEW YORK.

SHOCK-ABSORBER.

1,125,942.

Specification of Letters Patent.

Patented Jan. 26, 1915.

Application filed June 7, 1911. Serial No. 631,719.

To all whom it may concern:

Be it known that I, ALVA W. BLANCHARD, a citizen of the United States, residing in the borough of Brooklyn, in the county of 5 Kings and State of New York, have invented certain new and useful Improvements in Shock-Absorbers, of which the following is a specification, reference being had therein to the accompanying drawings, forming part 10 thereof.

My invention relates generally to shock-absorbers for vehicles and more particularly to shock-absorbers of the hydraulic type.

Among the objects of my invention are 15 extreme simplicity of construction, inexpensiveness of manufacture and maintenance, a high degree of effectiveness of operation, non-liability to derangement, accessibility of parts, obviation of the possibility of violent 20 contact of relatively movable parts, and obviation of rattling.

More particular objects and advantages of my invention will hereinafter appear.

My invention includes a liquid-containing 25 cylinder which is closed to the atmosphere at one side of a piston and open to the atmosphere at the other side of the piston, there being restricted liquid-conveying communication from one side of the piston to the other in all positions of piston movement. More particularly, such communication is of constant extent for each direction of movement of the piston and the movements of the piston in one direction, for example, toward the closed end of the cylinder are opposed by a comparatively slight resistance, but the movements of the piston in the opposite direction or away from the closed end of the cylinder are opposed by a 30 comparatively great resistance, this latter resistance, however, being entirely due to the pressure of the outer air or atmosphere. In this connection as a means for causing the difference in resistance, my invention includes a check-valve of appropriate and 35 novel construction.

My invention also includes such a liquid-containing cylinder closed at one end and in which is a hollow piston having an inner 40 head, there being free communication from the interior of the piston to the atmosphere and restricted communication from the interior of the piston to the inside of the cylinder inward from the piston head at all 45 points of piston movement.

My invention also includes a hollow pis-

ton having inner and outer heads and having an opening to the atmosphere spaced downward from the outer head in position to be covered by the cylinder so that the air contained in the piston will act as a cushion to prevent contact of the piston and the cylinder head. 60

In a hollow liquid-receiving piston open to or freely communicating with the atmosphere, my invention also includes splash fenders to prevent the splashing out of the liquid through the opening to the atmosphere. 65

In carrying out my invention, I provide 70 springs reactive between the piston and its support and between the cylinder and its support to take up wear and to prevent rattling at the joints at these points of connection.

My invention also includes other features 75 of construction and combinations of parts, as will appear from the following description.

I shall now describe the shock-absorber 80 embodying my invention illustrated in the accompanying drawings and shall thereafter point out my invention in claims.

Figure 1 is an elevation partly broken away showing the shock-absorber in place 85 on the chassis of an automobile. Fig. 2 is an enlarged central vertical section of the shock-absorber and its attaching brackets. Fig. 3 is a horizontal section on a plane indicated by the line 3—3 of Fig. 2 as viewed 90 from above. Fig. 4 is a similar view on a plane indicated by the line 4—4 of Fig. 2. Fig. 5 is a further enlarged plan of the valve bushing and valve carried thereby. Fig. 6 is an inverted plan of the same. 95

In the shock-absorber illustrated in the drawings, a vertically disposed cylinder 11 is closed at its lower end and is completely open at its upper end. Within this cylinder 11 is a hollow piston 12 provided as shown 100 with both inner or lower and outer or upper piston heads. The piston 12 telescopes into the upper open end of the cylinder 11 and may be received substantially completely therein and is entirely removable from the cylinder when the shock-absorber is not attached to a vehicle, in the drawings the piston being shown at about a middle position in the cylinder. The cylindrical wall of the piston has openings 13 therein slightly 105 spaced below the upper cylinder head and providing unrestricted or free communica- 110

tion from the interior of the piston to the atmosphere above the maximum level of the shock-absorbing liquid. The cylinder 11 is nearly filled with liquid, as indicated in Fig. 5 2, such as a lubricating oil, and the lower piston head has therein an upwardly opening check-valve for controlling the flow of liquid from the cylinder 11 to the interior of the hollow piston 12 and vice versa.

10 A slightly flanged valve bushing 14 screws upward through the lower piston head. The valve bushing 14 is cup-shaped, having upon its upper side a circular recess 15 outwardly from which or at the top of the bushing is 15 formed a valve seat. A valve-guiding post 16 projects upward from the center of the valve bushing, such post being shown as an ordinary small bolt screwed into the valve bushing and the head of which forms 20 a valve-limiting abutment. A valve disk 17 is slidable and freely rotatable upon the post 15. Liquid-conveying openings 18 are provided through the valve bushing 14, these 25 openings connecting the recess 15 with the cylinder below the piston and being shown as six in number arranged in a circular series. The valve disk 17 has therein two small liquid-conveying openings 19 which when the valve disk is upon its seat (Fig. 2) 30 form the only communication between the recess 15 and the interior of the piston 12.

It is to be noted here that the circular recess 15 is a liquid-conveying channel providing communication between the openings 35 18 in the valve bushing and the openings 19 in the valve disk without regard to the rotation of the valve disk 17, which is thus permitted to freely assume any rotational position. The total cross-sectional area of the 40 openings 19 in the valve disk 17 is much less than the corresponding total area of the openings 18 in the valve bushing 14. As the piston 12 moves into the cylinder 11 the valve disk 17 will lift and the liquid in the 45 cylinder below the piston will flow into the piston, the large number of large openings 18 in the valve bushing offering a comparatively slight resistance to the movement of the liquid into the hollow piston. However, 50 when the piston 12 moves upwardly in the cylinder 11 the valve disk 17 will seat upon the bushing 14 and liquid can only pass out of the piston and into the cylinder below the piston through the two small openings 19 55 in the valve disk 17. Therefore, a comparatively slight resistance is offered to the downward movement of the piston or the upward movement of the cylinder and a comparatively great resistance is offered to 60 the upward movement of the piston or the downward movement of the cylinder.

Air is freely admitted above the lower piston head and above the liquid in the piston, through the openings 13 near the upper end of the piston; and it is to be noted that

the cylinder and the piston are held together by the pressure of the atmosphere, and also that it is atmospheric pressure which forces the liquid from the piston through the restricted openings 19 in the 70 valve disk 17 when a separating movement between the piston and cylinder takes place. That is to say, the resistance to separation of the piston and cylinder, or to movement of the piston away from the closed end of 75 the cylinder, is provided solely by the barometric pressure of the outer air or atmosphere.

The openings 13 from the piston to the atmosphere are so located that they will be 80 closed by the wall of the cylinder before the piston reaches the bottom of the cylinder so that the air will be trapped in the piston as the end of the stroke is approached and will act as a cushion to prevent violent contact of the piston with the bottom of the cylinder.

The cylinder 11 is carried by the axle and the piston 12 is carried by the frame forming a part of the vehicle body. For attaching 90 purposes, the head of the cylinder 11 is centrally provided with a screw-threaded stem 20 and the upper or outer head of the piston 12 is similarly provided with a similar stem 21. An L-shaped cylinder-supporting 95 bracket 22 is secured to the vehicle axle by a U-bolt 23 acting as a clamp (Fig. 1), and a horizontally-projecting piston-supporting bracket 24 has a base flange secured to the side member of the vehicle frame. The cylinder stem 20 extends downward and passes loosely through a tapered stem-receiving opening of somewhat larger diameter than the stem in the horizontal arm of the cylinder-supporting bracket near its end. A nut 100 25 screws on the cylinder stem 20 below the bracket arm and has its upper face spherically rounded to fit into a complementary socket formed in the lower face of the bracket arm, thereby providing for limited 105 pivotal movement in all directions. A stiff curved leaf spring 26, shown as a four-pronged star spring, through a central hole in which the cylinder stem 20 passes, presses at its central part upon the upper surface 110 of the bracket arm and presses at its end parts against the head of the cylinder 11, this spring keeping the joint tight, taking up wear and preventing rattling. The piston stem 21 passes loosely through a somewhat larger tapered aperture in the horizontally-projecting piston-supporting bracket 24 and is provided above the bracket with a nut 27, which is spherically rounded on its lower side to pivotally fit into a complementary socket in the upper face of the bracket.

A stiff curved leaf spring 28 of star shape surrounds the piston stem 21 between the piston supporting bracket 24 and the upper piston head, at its center pressing upwardly 115 120 125 130

against the bracket and at its ends pressing downward on the upper piston head. The construction and function of the spring 28 above the piston are similar to the construction and function of the spring 26 below the cylinder. The resistance to the downward movement of the piston 12 or to the upward movement of the cylinder 11 being, as hereinbefore explained, comparatively slight, the 10 springs 26 and 28 are strong enough to transmit this movement from the supporting brackets 22 and 24 without yielding, as any yielding would cause rattling.

A thin sheet metal shell 29 is carried by 15 the piston 12 and extends down over the upper open end of the cylinder 11, covering the upper end of the piston 12, protecting it and the cylinder from dust and grit, and also concealing the piston from view and 20 giving a good finish. The shell 29 is spaced a substantial distance from the wall of the cylinder 11, longitudinal guide ribs 30 shown as four in number (Fig. 4), being provided on the outer surface of the cylinder 25 against which the shell 29 fits sufficiently tight to prevent rattling. Perfectly free access of air entering and leaving the hollow piston 12 is had between these ribs 30. The shell 29 is closed at its top and extends over 30 the upper piston head beneath the curved leaf spring 28 by which it is held in place.

In the operation of the device the liquid 35 within the piston 12 is necessarily somewhat agitated, and to guard against its loss by splashing out through the openings 13 near the upper end of the piston, I provide splash fenders 31 at the upper part of the inside of the piston. These splash fenders are inwardly and downwardly extending plates or 40 walls formed integral with the cylindrical side wall of the piston and extending more than half way across the interior piston space alternately in overlapping relation from opposite sides, four such fenders being shown, 45 two at each side (Figs. 2 and 4). Ordinary lubricating oil may be used as the shock absorbing liquid and should a little of it be lost it may be replenished from time to time through an oil supply opening in the upper 50 piston head, this opening being closed by an ordinary screw-plug 32.

The details of operation have been described along with the description of the construction, but the general operation of 55 the device considered as a whole requires some further explanation. The cylinder 11 being carried by the axle of the vehicle and the piston 12 being carried by the vehicle frame, it is to be noted that the downward 60 movement of the frame or the upward movement of the axle will meet with comparatively slight resistance, whereas the upward movement of the vehicle frame or the downward movement of the axle, these being the 65 movements due to the recoil of the vehicle

springs, is opposed by a comparatively great resistance. This resistance to recoil, however, is controlled solely by the pressure of the outer air or atmosphere, there being no compressive action in any part of the operation of the device except only in the extreme position when the openings 13 near the upper end of the piston are closed by the cylinder wall. This is an extreme condition and under ordinary working these openings 70 13 are uncovered. It should be noted that the barometric or atmospheric pressure constitutes the maximum resistance to which the piston 12 is subjected in its upward or outward movement in the cylinder 11. 75 With a very strong vehicle spring the recoil might in some cases be sufficient to overcome the atmospheric pressure and produce a vacuum in the cylinder below the piston. This condition could only occur following 80 an extreme position of movement together of the piston and cylinder and could only endure while the vehicle spring was under greatest tension, so that under no possibility could there be a rebound effect at the limit 85 of the separating movement. Moreover, the possibility of the production of such a vacuum is directly dependent upon the cross-sectional area of the piston and if desired this can be made large enough to pre- 90 clude the possibility of a vacuum ever being formed therein. I have found in practice that with a piston diameter of three inches excellent results are obtained. In case of the production of a vacuum, as above mentioned, the level of the shock-absorbing liquid may rise above the open upper end of the cylinder 11, but obviously none of this liquid could be lost by overflow, as all of the liquid raised would be contained within the 95 hollow piston 12.

Among the great advantages of the open top cylinder and the hollow piston freely communicating with the atmosphere, are the avoidance of the necessity of any packing. 100 No joint has to be tight except the long sliding contact of the piston and cylinder, and the abundance of lubricating oil assures both tightness and effective lubrication at this joint. Another great advantage is the ease 105 with which the device may be supplied with oil and the supply replenished as well as that no special kind of oil is required.

While there is nothing about the device liable to get out of order, to give way or 110 soon wear out, yet it is to be noted that all parts are readily accessible for inspection and renewal. For example, by merely disconnecting either the piston or the cylinder from the vehicle, access is had to the check 115 valve which may be removed *in toto* merely by unscrewing the valve bushing 14. All other parts are even more readily accessible.

It is obvious that various modifications may be made in the construction shown in 120

the drawings and above particularly described within the principle and scope of my invention.

I claim:

- 5 1. A shock-absorber comprising a liquid-containing cylinder, and a piston movable longitudinally in the cylinder, the cylinder being closed to the atmosphere at one side of the piston and being freely open to the 10 atmosphere at the other side of the piston so as to subject the liquid in the cylinder to atmospheric pressure only at one side only of the piston, such atmospheric pressure being the maximum resistance to the movement of 15 the piston in one direction in the cylinder, freely open restricted communication for the liquid being provided from one side to the other of the piston in all positions of the piston in the cylinder and means being provided to prevent the liquid overflowing from the open side of the cylinder should the piston move with sufficient force to overcome the pressure of the atmosphere.
2. A shock-absorber comprising a liquid-containing cylinder, a piston movable longitudinally in the cylinder, the cylinder being closed to the atmosphere at one side of the piston and being freely open to the atmosphere at the other side of the piston, atmospheric pressure constituting the maximum resistance to the movement of the piston away from the closed and toward the open side of the cylinder, and a check-valve controlling the liquid and arranged to resist the movement of the piston in the cylinder with a comparatively great resistance in one direction of relative movement of the piston in the cylinder and with a comparatively slight resistance in the other direction of relative movement of the piston in the cylinder and means being provided to prevent the liquid overflowing from the open side of the cylinder should the piston move with sufficient force to overcome the pressure of the atmosphere.
3. A shock-absorber comprising a liquid-containing cylinder, a piston movable longitudinally in the cylinder, the cylinder being closed to the atmosphere at one side of the piston and being freely open to the atmosphere at the other side of the piston, atmospheric pressure constituting the maximum resistance to the movement of the piston away from the closed and toward the open side of the cylinder, and a liquid-controlling check-valve arranged to offer a comparatively slight resistance to the movement of the liquid past the piston from the closed side to the open side of the cylinder and to offer a comparatively great resistance to the movement of the liquid in the opposite direction and means being provided to prevent the liquid overflowing from the open side of the cylinder when the piston moves 65 against the comparatively great resistance

as controlled and limited by the pressure of the atmosphere.

4. A shock-absorber comprising a liquid-containing cylinder, and a piston movable longitudinally in the cylinder, the cylinder being closed to the atmosphere at one side of the piston and being freely open to the atmosphere at the other side of the piston so as to subject the liquid in the cylinder to atmospheric pressure only at one side only of the piston such atmospheric pressure being the maximum resistance to the movement of the piston in one direction in the cylinder, freely open restricted communication of constant extent for each direction of piston movement being provided for the liquid from one side to the other of the piston in all positions of the piston in the cylinder and means being provided to prevent the liquid overflowing from the open side of the cylinder should the piston move with sufficient force to overcome the pressure of the atmosphere.

5. In combination with a vehicle body and its axle, and a spring between them; a shock-absorber comprising a substantially vertical liquid-containing cylinder carried by the axle and open at the top, and in the cylinder a hollow liquid-receiving piston having a closed upper head and a lower head having therein a restricted opening, the upper part of the piston being movable above the cylinder wall and the piston having an opening to the atmosphere in position to be covered by the cylinder wall before the piston reaches its lowermost position therein.

6. In combination with a vehicle body and its axle, and a spring between them; a shock-absorber comprising a substantially vertical liquid-containing cylinder carried by the axle and open at the top, a hollow liquid-receiving piston in the cylinder having a restricted communication to the interior of the cylinder and having a closed upper end, the upper end of the piston being movable above the wall of the cylinder and the piston having an opening from its interior to the atmosphere in position to be covered by the wall of the cylinder before the piston reaches its lowermost position therein, and an outer shell carried by the upper end of the piston and extending downward over the piston opening and over the upper end of the cylinder in spaced relation to the piston and the cylinder to provide for free access of air to the interior of the piston, the cylinder being provided with spaced longitudinal guides for the outer shell.

7. A shock-absorber comprising a substantially vertical liquid-containing cylinder open at the top, and in the cylinder a hollow liquid-receiving piston having restricted communication from its interior to the cylinder and having an opening at its

upper part providing free communication with the atmosphere, the inside of the piston being provided with splash-fenders to prevent the liquid from splashing out through 5 the opening to the atmosphere.

8. A shock-absorber comprising a substantially vertical liquid-containing cylinder open at the top, and in the cylinder a hollow liquid-receiving piston having restricted communication from its interior to the cylinder and having an opening at its upper part providing free communication with the atmosphere, the inside of the piston being provided at the upper part with 10 downwardly inclined alternately overlapping splash fenders.

9. A shock-absorber comprising a substantially vertical liquid-containing cylinder open at the top, and in the cylinder a hollow liquid-receiving piston having a lower head, the upper portion of the piston being movable above the top of the cylinder wall and having an opening to the atmosphere above the maximum liquid level 15 to subject the liquid in the cylinder and piston to atmospheric pressure only at the upper side of the piston, such atmospheric pressure being the maximum resistance to which the piston is subjected in its upward 20 movement in the cylinder, the lower end of the cylinder being closed to the atmosphere, freely open restricted communication for the liquid being provided between the interior of the hollow piston and the interior 25 of the cylinder below the piston in all positions of the piston in the cylinder.

10. A shock-absorber comprising a substantially vertical liquid-containing cylinder open at the top, in the cylinder a hollow liquid-receiving piston having a lower head, the upper portion of the piston being movable above the top of the cylinder wall and having an opening to the atmosphere above the maximum liquid level to subject the liquid in the cylinder and piston to atmospheric pressure only at the upper side of the piston, such atmospheric pressure being the maximum resistance to which the piston is subjected in its upward movement in the cylinder, the lower end of the cylinder being closed to the atmosphere, and a check-valve controlling the liquid and arranged to resist the movement of the piston in the cylinder with a comparatively great resistance 45 50

in one direction of relative movement of the piston in the cylinder and with a comparatively slight resistance in the other direction of relative movement of the piston in the cylinder.

11. A shock-absorber comprising a substantially vertical liquid-containing cylinder open at the top, in the cylinder a hollow liquid-receiving piston having a lower head, the upper portion of the piston being movable above the top of the cylinder wall and having an opening to the atmosphere above the maximum liquid level to subject the liquid in the cylinder and piston to atmospheric pressure only at the upper side of the piston, such atmospheric pressure being the maximum resistance to which the piston is subjected in its upward movement in the cylinder, the lower end of the cylinder being closed to the atmosphere, and a liquid-controlling check-valve arranged to offer a comparatively slight resistance to the movement of the liquid from the cylinder below the piston into the hollow piston and to cooperate with atmospheric pressure to offer a comparatively great resistance to the movement of the liquid in the opposite direction.

12. A shock-absorber comprising a substantially vertical liquid-containing cylinder open at the top, and in the cylinder a hollow liquid-receiving piston having a lower head, the upper portion of the piston being movable above the top of the cylinder wall and having an opening to the atmosphere above the maximum liquid level to subject the liquid in the cylinder and piston to atmospheric pressure only at the upper side of the piston, such atmospheric pressure being the maximum resistance to which the piston is subjected in its upward movement in the cylinder, the lower end of the cylinder being closed to the atmosphere, freely open restricted communication of constant extent for each direction of piston movement being provided for the liquid from one side to the other of the piston head in all positions of the piston in the cylinder.

In testimony whereof I have affixed my signature in presence of two witnesses.
